(57) **CLAIM**

The ornamental design for a fishing reel frame, as shown and described.

DESCRIPTION

FIG. 1 is a right side elevation view of the fishing reel frame of the invention.

FIG. 2 is a left side elevation view of the fishing reel frame of FIG. 1.

FIG. 3 is a right rear angled top view of the fishing reel frame of FIG. 1.

FIG. 4 is a right front angled top view of the fishing reel frame of FIG. 1.

FIG. 5 is a left rear angled top view of the fishing reel frame of FIG. 1.

FIG. 6 is a front elevation view of the fishing reel frame of FIG. 1.

FIG. 7 is a rear elevation view of the fishing reel frame of FIG. 1; and,

FIG. 8 is a top view of the fishing reel frame of FIG. 1.

The broken line showing of environment in the drawings is for illustrative purposes only and forms no part of the claimed design.
